(57) **CLAIM**

The ornamental design for a tyre portion, as shown and described.

DESCRIPTION

FIG. 1 is a front view of a tyre portion according to our new design;

FIG. 2 is a perspective view thereof;

FIG. 3 is an enlarged view of the section indicated in FIG. 1; and,

FIG. 4 is an enlarged view of the section indicated in FIG. 2.

The part of the drawings shown with a reduced tonal value, along with the broken-line perimeter, illustrates a portion of the tyre portion that forms no part of the claimed design.
